No. 766,704.

PATENTED AUG. 2, 1904.

D. KOPS.
CORSET ATTACHMENT.
APPLICATION FILED JULY 1, 1903.

NO MODEL.

UNITED STATES PATENT OFFICE.

DANIEL KOPS, OF NEW YORK, N. Y.

CORSET ATTACHMENT.

SPECIFICATION forming part of Letters Patent No. 766,704, dated August 2, 1904.

Application filed July 1, 1903. Serial No. 163,834. (No model.)

To all whom it may concern:

Be it known that I, DANIEL KOPS, a citizen of the United States, residing at the borough of Manhattan, city, county, and State of New York, have invented an Improvement in Corset Attachments, of which the following is a specification.

My invention relates to a device either attached to or adapted to be attached to a corset and to which hose-supporters for women's wear may be connected. The object attained by the device of my invention when secured to the lower front portion of the corset is to keep the parts of the corset distended or under tension and prevent a drawing together or buckling of said parts under the strain exerted by the hose-supporter.

In my improvement I provide a strip of stiffened fabric with converging overlying straps extending from the ends of such strip with the parts of such straps passing in opposite directions through the mortises of a slide-plate. This slide-plate preferably has a mortise for attachment thereto of a fabric section to which a hose-supporter may be connected, or said hose-supporter may be connected directly to the slide-plate. Duplicate parts so constructed occupy positions at the lower front portions of the corset upon each side of the center secured to the corset upon the under surface. The stiffened fabric strip is preferably provided with bones longitudinally placed and is secured to a front steel and other steels by rivets or eyelets.

In the drawings, Figure 1 is an elevation of the lower front and central portion of a corset, illustrating my improvement. Fig. 2 is an elevation of the inner surface at the lower front portion at one side, and Fig. 3 is a cross-section at $\alpha\alpha$ of Fig. 1.

The device comprising my invention is especially adapted to be applied to the under surface of the corset and to be at its respective ends connected thereto, one point of connection being the front steel and the other and distant point of connection being a steel in the front portion of the corset distant from the front steel about three inches, and as the devices are alike it will serve the purpose of the description to describe only one structure

in which the fabric strip is preferably composed of an outer fabric part a and an inner fabric part a' . Between these are bone stiffeners b . These fabric strips are to be connected by outside edge lines of sewing and a central or intermediate line of sewing, which lines of sewing substantially form bone-pockets in said strips of fabric.

The fabric strip, composed of the parts a a' , is preferably overturned at the respective ends 60 and the converging overlying straps d e are at their ends connected to the ends of said fabric strip at 4. These straps d e pass through mortises 2 3 of the slide-plate f , and this slide-plate is provided with a third mortise 5 at the 65 lower edge thereof, and to this slide-plate f at said mortise 5 a fabric section h may be secured which serves for the attachment thereto of the hose-supporters, or, if preferred, the elastic strip of the hose-supporters may be directly connected to said slide-plate f by passing the end of the same through the mortise 5, bending the same over, and sewing the end to the adjacent portion.

The structure just described in its entirety 75 is advantageously secured to the lower front portion of the corset, as hereinbefore intimated, by the rivets c in the manufacture of the corset. It is, however, apparent that these articles may be sold independent of the corset 80 and may be secured to corsets already in use by the wearers either by rivets, eyelets, or even by sewing, for the performance of the functions of the structure.

The parts a a' comprising the fabric strip 85 are connected together by the central and outer lines of sewing 6 7 8, which at the same time form within and between said parts pockets for the bone stiffeners b , and when this stiffened fabric strip is secured to the lower front 90 portion of the corset, preferably upon the inner surface, it is advantageous not only to connect the same by the end rivets c , but also by lines of sewing which correspond to the lines 6 7 8, because where the device is made for attachment to a corset it is complete in itself except the fact of the attaching devices, and where it is originally made and secured to the corset these lines of sewing 6, 7, and 8 may be employed not only for connecting the parts a a' to- 100

gether and forming the pockets for the bone stiffeners, but also for connecting said fabric parts to the body of the corset at the same time.

In the operation of the device and when the hose-supporters are either connected to the fabric sections *h* or directly to the slide-plates *f* these slide-plates will move in relation to the overlying straps *d e* for the accommodation of the line of draft, so that the same is direct from the corset. This line of draft may even change with the position of the wearer or the movement in walking, and in any event the slide-plates by their shifting function will accommodate the line of draft. A further function performed by the structure and by the tension applied by the hose-supporters is to draw and hold down the corset to the figure of the wearer at the lower front portion, the drawing strain being applied directly to the corset-body (rather than to some flexible appendage thereof) and at firm connections with the lower ends of the main front and other steels, which compels the lower portion and edge of the corset to bend against the body, not only causing the same to fit snugly, but to hold in the abdomen and assist the figure of the wearer.

I do not herein limit myself to the device by which the structure is connected to the corset nor to originally connecting said structure to a corset, as it is apparent that the structures may be sold separate from the corset for attachment by the wearer. I further do not limit myself to the character of the stiffening devices employed between the parts *a a'* of the fabric strip, as these may be varied without departing from the invention.

From the illustration and the foregoing description it will be apparent when the structure is connected to the lower front portion of the corset that the same has the effect of keeping this portion of the corset in a distended condition and of holding the same in such condition regardless of the tension of the hose-supporters, so that a smooth even surface is always maintained at this part of the corset.

I claim as my invention—

1. As a corset attachment, a fabric strip comprising two overlying parts, bone stiffeners between said parts, means for permanently connecting said parts together with the bones secured between the same, converging overlying straps connected at their respective ends to the ends of said stiffened fabric strip, and a slide-plate having mortises through which the parts of said overlying straps pass and upon which straps said slide-plate is movable.

2. As a corset attachment, a fabric strip comprising two overlying parts, bone stiffeners between said parts, lines of sewing at the respective edges of the strip outside of the bone stiffeners, and an intermediate or central line of sewing between the bone stiffeners connecting the parts together and inclosing the bones,

converging overlying straps connected at their respective ends to the ends of said stiffened fabric strip, and a slide-plate having mortises through which the said overlying straps pass and upon which strap said slide-plate is movable.

3. As a corset attachment, a fabric strip comprising two overlying parts, bone stiffeners between said parts, lines of sewing at the respective edges of the strip outside of the bone stiffeners, an intermediate or central line of sewing between the bone stiffeners connecting the parts together and inclosing the bones, converging overlying straps connected at their respective ends to the ends of said stiffened fabric strip, a slide-plate having mortises through which the said overlying straps pass and upon which straps said slide-plate is movable, and said slide-plate having an additional mortise to which the straps of hose-supporters may be connected.

4. As a corset attachment, a fabric strip comprising two overlying parts, bone stiffeners between said parts, lines of sewing at the respective edges of the strip outside of the bone stiffeners, an intermediate or central line of sewing between the bone stiffeners connecting the parts together and inclosing the bones, converging overlying straps connected at their respective ends to the ends of said stiffened fabric strip, a slide-plate having mortises through which straps the said overlying straps pass and upon which said slide-plate is movable, said slide-plate having an additional mortise along its lower edge and a fabric section connected to said slide-plate at said mortise and to which fabric section the ends of hose-supporters may be connected.

5. As a corset attachment, a fabric strip comprising two overlying parts, bone stiffeners between said parts, lines of sewing at the respective edges of the strip outside of the bone stiffeners, an intermediate or central line of sewing between the bone stiffeners connecting the parts together and inclosing the bones, converging overlying straps connected at their respective ends to the ends of said stiffened fabric strip, a slide-plate having mortises through which straps the said overlying straps pass and upon which said slide-plate is movable, and fastening devices at the respective ends of said stiffening fabric strip connecting the same to the lower front portion of the corset one fastening device passing through the front steel and the other through a steel at the end of said strip.

6. The combination with a corset, of a fabric strip comprising two overlying parts connected together and to the fabric body of the corset by a central and parallel edge lines of sewing forming in and between said parts bone-pockets, bone stiffeners received in said pockets and the respective ends of said fabric strip overturned, fastening devices securing the respective ends of the fabric strip to the inner

surface of the corset at the lower front portion, one fastening device passing through a front steel and the other fastening device through an adjacent steel at the end thereof, 5 converging overlying straps connected at their respective ends to the ends of said stiffened fabric strip, a slide - plate having mortises through which straps the said overlying straps pass and upon which said slide-plate is movable, 10 said slide-plate having an additional mortise along its lower edge to which fabric may be connected for the hose - supporters, said parts being duplicated upon each half of the corset.

15 7. As a corset attachment, a stiffened fabric

strip, comprising two overlying parts and means for connecting said parts together, the respective ends of said stiffened fabric strip being overturned at an inclination, converging overlying straps connected at their ends 20 to the ends of the said stiffened fabric strip, and a slide - plate having mortises therein through which the parts of the converging overlying straps pass.

Signed by me this 26th day of June, 1903. 25

DANIEL KOPS.
